UNITED STATES PATENT OFFICE.

WILLIAM C. DEMAIN, OF MEDFORD, MASSACHUSETTS.

PLATE-PRINTING PRESS.

SPECIFICATION forming part of Letters Patent No. 269,393, dated December 19, 1882.

Application filed May 24, 1882. (No model.)

To all whom it may concern:

Be it known that I, WILLIAM CHARLES DEMAIN, of Medford, in the county of Middlesex and State of Massachusetts, have invented certain new and useful Improvements in Plate-Printing Presses, of which the following, taken in connection with the accompanying drawings, is a specification.

My invention relates especially to improvements in the device for connecting the impression-cylinder with the plate-carrying carriage or "plank" to cause them to move in unison, and to an improved adjustable clamp for securing the lower end of the blanket, which will be best understood by reference to the following description of the drawings, in which—

Figure 1 is a vertical section of a plate-printing press embodying my present invention, the cutting plane being just inside of one of the side frames. Fig. 2 is a horizontal section on line *xx* on Fig. 1. Fig. 3 is a section of one end of the impression-cylinder and adjustable arm secured thereto. Fig. 4 is an elevation of the clamp for holding the end of the blanket, and Fig. 5 is a section of the same on line *yy* on Fig. 4.

A *A* are the two side frames of the machine, connected together by suitable tie-rods, *a a*, and having mounted in suitable bearings there-

30 in the cylinder *B*, rolls *C C*, and impression-cylinder *D*.

The bed-supporting plank *E* is mounted upon the cylinder *B* and rolls *C C*, and carries near its front end the bed *F*, to which is secured the gage *c*, against which the front edge of the plate *d* is placed, as shown. After the impression is given the plank *E* is moved toward the front of the machine by the expansion of the springs *g g*, surrounding the rods

40 *e e*, which are secured at their front ends to the plank *E*.

H is an arm pivoted at its rear end to the adjustable bar *I*, secured to the plank *E* by a bolt, *n'*, passing through the slot *n* in said bar. The arm *H* is notched at its forward end, and is supported in a horizontal position, or nearly so, by the spring *J*, as shown.

The press as thus described forms no part of my present invention, as it is substantially the same in construction and operation as the one shown and described in Letters Patent No.

256,413, granted to me as the assignee of James Tregurtha, April 11, 1882.

I will now describe the devices which constitute my present invention.

Secured upon one end of the roll *D* is the adjustable radius-arm *G*, provided with a ring portion, which surrounds the roll *D*, said ring portion having a joint, *b*, upon one side thereof. Two ears—one upon each side of the joint *b*—are connected together by the bolt *f*, by which means the joint *b* is closed, or partly closed, to compress the ring firmly around the roll *D*.

From the inner circumference of the ring portion of the arm *G* project two flanges or ribs, *h h*, which fit into grooves turned in the roll *D* near its end, as shown in Fig. 3, in order to prevent the arm *G* from slipping off the roll *D* when adjusting said ring about the axis of the roll. In securing the arm *G* in position the bolt *f* is first removed. The ring is then sprung open until it will slip over the portion *i* between the grooves before mentioned, and when the ring comes in contact with the shoulder *j* on the roll *D*, the bolt *f* may be inserted and screwed up, thus clamping the ring firmly in position. The depth of the grooves in the roll *D*, which receive the flanges *h h*, is but slight; but it is sufficient to prevent the arm *G* from slipping endwise of said roll. I prefer to make the arm *G* of cast-steel to obviate the danger of breakage when springing the ring into position.

In the outer end of the arm *G* is secured the stud *l*, which, at the proper time in the rotation of the roll *D*, engages with the notched forward end of the arm *H* to carry the plank *E* and bed *F* into position to give the impression, as described in the Letters Patent before cited. For the purpose of adjusting the various parts, graduated scales are cut or affixed to the plank *E*, the bed *F*, and the roll *D*, the same as described in the above-mentioned Letters Patent.

The second portion of my invention pertains to the adjustable clamp *L* for securing the lower end of the blanket to the plank *E*. This clamp is made in two parts, *o* and *p*, the lower part, *p*, having a rearwardly-projecting horizontal foot, *q*, provided with a lip, *r*, which extends longitudinally thereof, and is fitted to a

groove, *m*, in the upper side of the plank *E*, said foot *g* being also provided with a slot, *r'*, by means of which and the thumb-screw *k* the clamp *L* may be firmly secured to and adjusted 5 upon the plank *E*. Two studs, *s s*, are screwed into the opposite ends of the piece *p*, and, passing through holes in the opposite ends of the upper portion, *o*, are provided at their upper ends with thumb-nuts *t t*, by means of which 10 the two portions of the clamp *L* are compressed upon the end of the blanket. Two springs, *s' s'*, surround the studs *s s* between the upper and lower portions of the clamp *L*, and act by their expansive force to open said clamp when 15 the thumb-nuts *t t* are unscrewed. Extending along the lower edge of the piece *o* are two ribs, *u u*, and upon the upper edge of the piece *p* is a single rib, *v*, which fits between the ribs *u u* when the clamp is closed, as shown in Fig. 20 5, the purpose of said ribs being to enable the clamp *L* to hold the blanket more securely.

What I claim as new, and desire to secure by Letters Patent of the United States, is—

1. In a plate-printing press, a **D**-cylinder provided at one end with a reduced portion, 25 the periphery of which reduced portion is of greater diameter in one part than in another, in combination with a radius arm or lever having a ring or hub fitted to said reduced portion of different diameters and cut apart upon one side, and a screw-bolt extending across said cut, and adapted to clamp the arm to the **D**-cylinder in any desired position.

2. The clamp *L*, provided with the slotted foot *g*, in combination with the plank *E* and 30 the clamping-bolt or thumb-screw *k*, all arranged and adapted to operate substantially as described.

Executed at Boston, Massachusetts, this 22d day of May, A. D. 1882.

WILLIAM CHARLES DEMAIN.
